His Attorney.

UNITED STATES PATENT OFFICE

2,511,666

AIR DEHUMIDIFIER FOR COMPARTMENTS

Samuel R. Barr, Bridgeport, Conn., assignor to
General Electric Company, a corporation of
New York

Application October 9, 1948, Serial No. 53,624

2 Claims. (Cl. 183—4.1)

1

My invention relates to drying apparatus and more particularly to an air dehumidifying unit such as may be placed in various types of compartments in order to remove moisture from the air within these compartments.

Heretofore most dehumidifying units have required that the moisture removing agent in the unit be replaced from time to time as it became saturated with moisture. Other units in which the desiccating agent could be reactivated required that the reactivating means be turned on and off manually.

One of the objects of my invention, therefore, is to provide a simple completely automatic dehumidifying unit which can be mounted easily in a compartment and requires little or no further attention after the installation.

Another object of my invention is to provide a dehumidifying unit whereby a desiccating agent included therein may automatically be reactivated after the absorption of a predetermined amount of moisture.

A further object of my invention is to provide a cabinet structure for such dehumidifying apparatus which operates automatically to open and close suitable ventilating apertures to enable the moisture laden atmosphere evaporated from an included desiccating agent during the reactivation thereof to be emitted outside of the dehumidifying apparatus.

In furtherance of these objects, I make use of the simple principle that as a desiccating agent absorbs moisture it also gains weight. In a preferred embodiment of my invention, the container for the desiccating agent is supported by resilient means and moves downward because of the increase in weight as the desiccating agent exposed to the air within the compartment absorbs moisture. At a predetermined point in its gradual descent, the container energizes a heating element placed near or within the desiccating agent. This heating element serves to reactivate the desiccating agent by evaporating the moisture it has absorbed. In order that the same water vapor will not be reabsorbed by the desiccating agent, automatic means are provided by which the water vapor escapes outside of the compartment while the desiccating agent is being reactivated.

Since the desiccating agents in common use today, such as silica gel, do not deteriorate or evaporate with use, the unit requires little or no further attention once it is installed and adjusted.

For a more complete understanding of my invention reference should be had to the accom-

2

panying drawing in which Fig. 1 is a vertical sectional view of a dehumidifying unit mounted within a compartment. Fig. 2 is a vertical view partly in section of the dehumidifying unit of Fig. 1 showing its position while the unit is being reactivated. Fig. 3 is a front view partly in section of the entire dehumidifying unit of Fig. 1. Fig. 4 is a vertical sectional view of a cabinet for this dehumidifying unit. Fig. 5 is a plan view, partly in section, of this dehumidifying unit.

Referring to the drawings, I have shown my invention in one form as applied to a compartment 1 having a door 2, a shelf 3 and a plurality of ventilating apertures 4 at the top. Although my dehumidifying unit may assume a variety of shapes and sizes and may be located anywhere within the compartment, I have shown it as comprising a rectangular cabinet 5 mounted at the rear of compartment 1 on shelf 3 directly beneath the apertures 4 and secured in place by such means as screws 6 and nut 7.

Within this dehumidifier cabinet 5, I have provided a smaller rectangular container 8 into which a desiccating agent 9, such as silica gel, is placed. A frame 10 (best seen in Fig. 3) holds perforated screens 11 through which air can pass at the front and back of this container 8. Attached to the upper portion of one side 12 of this container 8 is a bifurcated hinge 13 comprising a pair of parallel extension arms 14, each arm having a hole 15 formed across its outer end spaced a short distance from the side 12 of said container 8. Hinge 13 fits over a hinge bracket 16 which is inserted between extension arms 14 and secured to the side of cabinet 5 by such means as screws 17 and 18. Bracket 16 also has a hole 19 formed within it correspondingly aligned to the holes 15 formed within the hinge extension arms 14. A hinge pin 20 is inserted through holes 15, 19 in order to make a pivotal connection 21. Holes 15, 19 are suitably formed to accommodate a ball bearing connection 22; best seen in Fig. 3.

In order to adjust the container 8 around pivot point 21 to a position substantially parallel to the base of cabinet 5, many different methods can be employed. One simple and effective method, best seen in Fig. 3, is to place a heavy spring 23 between pivot point 21 and the side 12 of the container 8 extending parallel thereto within the space between the hinge extension arms 14. Spring 23 is hooked at its upper end into a hole 24 formed in a projecting flange 25 of hinge bracket 16. The lower end of spring 23 is adjustably secured to the side 12 of the container 8 by an eye bolt 26 to which spring 23 is attached.

Eye bolt 26 is inserted through a suitable aperture 27 in a conventional L-shaped bracket 28 secured to the lower portion 29 of side 12 of the container 8 by such means as screws 30. The tension of spring 23 is adjusted by wing nut 31 threaded to eye bolt 26 beneath the L-shaped bracket 28.

A heating element 32 which in one form may comprise a sheathed heater unit having a U-shaped outer enclosing tube 33 and an inner heating wire 34 electrically insulated from the tube is placed in or near container 8. In the preferred embodiment of my invention illustrated in Fig. 3, heating element 32 is immersed within the desiccating agent 9. The arms 35 of the U-shaped heating element 32 are inserted through suitable collars 36 in the top of the container 8. These collars 36 serve to position the heating element 32.

A sensitive switch 37 is adjustably secured to the rear of cabinet 5 adjacent to the top of container 8 by such means as screws 38 and nuts 39 inserted within a pair of elongated slots 40 in a supporting bracket 41. The switch 37 is attached to the bracket 41 by such means as screws 42 and nuts 43. The bracket 41 has a slight pitch; and a small measure of both vertical and horizontal adjustment of switch 37 may be obtained by loosening screws 38, moving bracket 41 as guided by the elongated slots 40, and retightening screws 38.

A laterally projecting contact arm 44 attached to the top of the container fits under the switching arm 45 of the switch 37 and serves to hold the switch open. A pair of terminal connecting wires 46, 47 are attached to the arms 35 of the heating element 32, one of these connecting wires 46 going directly through an aperture in grommet 48 in the cabinet 5 to the electric current source (not shown) and the other of these wires 47 going to terminal 49 of the electric switch 37. Another terminal connecting wire 50 is attached to the other terminal 51 of switch 37 and extends out through the aperture in grommet 48 to the other side of the electric current source (not shown).

The front of the cabinet 5 is enclosed by an upper door 52 and a lower door 53 suspended on hinges 54 which are pivotally attached to cylindrical hinge rods 55. These rods 55 extend the entire width of the cabinet 5 and are inserted through suitable holes 56 in each side of the cabinet 5. The upper door 52 has an upper portion 57 and a lower portion 58 forming an obtuse angle and pivotally mounted on a cylindrical hinge rod 55 at the vertex of this angle on the top front corner 59 of cabinet 5. The upper portion 57 closes the top of the cabinet 5 when the lower portion 58 is slightly open.

During the interval that the desiccating agent 9 within the container 8 is absorbing moisture, doors 52, 53 are respectively held slightly open at the bottom by an upper supporting arm 60 and a lower supporting arm 61 located to one side of the container 8 and having a generally arched configuration. One leg 62 of each arch is secured to the rear of cabinet 5 by such means as screws 63 and nuts 64, while the other leg 65 of the arch holds the door open. Supporting arms 60, 61 are composed of two or more dissimilar metals having different thermal coefficients of expansion secured together lengthwise to form a unitary thermostatic bar. They are constructed to move inwardly as illustrated in

Fig. 4, upon the application of heat; thereby allowing the doors 52, 53 to close. When the lower portion 58 of the upper door 52 closes due to the inward movement of its supporting arm 60, the upper portion 57 moves open under the force of a small wire spring 66 hooked to a pin 67 which is attached to a side of cabinet 5. This spring encircles the hinge rod 55 and extends under the upper portion 57 of the door 52. Although I have shown the cabinet 5 as having two doors 52 and 53 respectively in order to obtain a large area of access between the internal desiccating agent and the atmosphere within the compartment, it is evident that, alternatively, only the angle-shaped upper door 52 and its associated supporting means need be employed; the remainder of the cabinet being entirely closed.

In the operation of my invention, the air within in the compartment 1 flows through the doors 52, 53 normally held open by supporting arms 60 and 61, to the desiccating agent 9 located within the container 8. This desiccating agent 9 removes the moisture from the air with which it comes in contact, and the dry air continues to circulate upward into the compartment 1. As the desiccating agent 9 absorbs moisture it gains weight, causing the container 8 gradually to descend. This downward motion is permitted by the pivotal connection 21 and the resilient spring 23. As the container moves downward the contact arm 44 releases the switching arm 45 of the switch 37 throwing the switch to its "on" position. This closes the circuit to the heating element 32 immersed within the desiccating agent 9, and the moisture absorbed by the desiccating agent is evaporated due to the application of heat, thereby reactivating the desiccating agent. As the temperature within the cabinet increases while the heating element is operating, the legs 65 of the bimetallic supporting arms 60, 61 move inwardly, causing the doors 52, 53 to close and simultaneously causing the upper portion 57 of the upper door 52 to open. The movement of these doors prevents the moisture-laden air within the cabinet 5 from once again circulating out to the compartment 1 during the reactivating period. Instead, this moisture-laden air circulates upward through the opening formed by the position of the upper portion 57 of the door 52, and out through the apertures 4 in the compartment 1 to the outside. As the moisture is evaporated from the desiccating agent 9, the container 8 becomes lighter and moves upward due to the action of spring 23, once again opening switch 37. The interval of time between reactivating periods can be increased or decreased by tightening or loosening the tension of spring 23, or by adjusting the position of switch 37.

As can be seen from the foregoing detailed description, the size and shape of the cabinet 5 or container 8 are not critical. They can be made to fit almost any compartment. The unit is easily adjustable and completely automatic once installed. Furthermore, since its automatic operation depends upon gravitational action, it is not subject to troubles inherent in units employing a mechanical motive force.

While I have shown a particular embodiment of my invention, it will be understood that I do not wish to be limited thereto since many modifications may be made and I, therefore, contemplate by the appended claims to cover such modifications as fall within the true spirit and scope of my invention.

What I claim as new and desire to secure by Letters Patent of the United States is:

1. A dehumidifying unit for drying the air within a compartment having ventilating apertures at the top thereof comprising a perforate container, a desiccating agent within said container, an outer enclosing cabinet for said container mounted beneath said ventilating apertures, said cabinet having a plurality of doors, the uppermost of said doors having upper and lower portions forming an obtuse angle and being pivotally mounted at the vertex of said angle at a top corner of said cabinet, the said upper portion closing the top of said cabinet when the lower portion is opened, a plurality of bimetallic supporting arms arranged normally to hold said doors open and constructed to close said doors upon the application of heat to said arms, said upper portion moving to an open position as the lower portion is closed upon the application of 20 heat, a pivotal connection between one side of said container and one side of said cabinet, resilient means for adjustably positioning said container around said pivotal connection, a heating element immersed within said desiccating agent, and a switch for energizing said heating element operated by the downward motion of said container as it absorbs moisture.

2. A cabinet for dehumidifying apparatus of the type including a container having a desiccating agent therewith comprising a member enclosing and supporting said container and having a vertically suspended door, said door having two portions forming an obtuse angle and being pivotally mounted at the vertex of said angle at 35

the top corner of said container, one of said portions closing an aperture in the top of said enclosing member when the other portion is in an open position, and the other portion of said door being arranged to close an aperture in the side of said container when said one portion is opened, a heating element within said enclosing member for reactivating said desiccating agent after an absorption of moisture thereby, and 10 thermally responsive supporting means arranged normally to maintain said other portion of said door in said opened position, but to move said one portion of said door to said open position when subjected to heat generated by said heating element during the reactivation of said desiccating agent.
